Egon Sorensen and William J. Hayes, Glen Riddle, Pa.,
assignors to Sunroc Corporation, Glen Riddle, Pa., a
corporation of Delaware

Application March 17, 1958, Serial No. 50,058

Term of patent 14 years

(Cl. D67—4)

FIG. I

FIG. 2

FIG. 3

Fig. 1 is a perspective view of a combined water cooler and refrigerator embodying our new design and with the door thereof closed;

Fig. 2 corresponds to and shows the combined water cooler and refrigerator of Fig. 1 with the door thereof open; and

Fig. 3 is an enlarged view in cross-section taken along line 3-3 of Fig. 1.

The side wall opposite the one shown is substantially the same as the illustrated side wall and the rear wall is conventional.

The dominant features of the design reside in the portions shown in full lines.

We claim:

The ornamental design for a combined water cooler and refrigerator, as shown and described.
